Int. Cl. D12—99

U.S. Cl. D14—3

FIG. 1 is a perspective view showing the top, one side and one end of a pallet showing our new design; and FIG. 2 is a perspective view showing the bottom, the other side and one end thereof.

The characteristic features of our design reside in the unitary form and the pebbled design on the upper and lower surfaces of the top portion thereof.

We claim:

The ornamental design for a pallet, as shown and described.
